PAGE 2

For convenience of illustration only, parts of the block pattern and the shingle pattern in the several views have been disclosed. It is to be understood that the block and shingle patterns are to continue throughout the adjacent plain areas to complete the respective patterns.

The dominant features of the design reside in the portions shown in full lines.

We claim:

The ornamental design for a house, as shown and described.
